UNITED STATES PATENT OFFICE.

DAVID M. MCCANLESS, OF ASHEVILLE, NORTH CAROLINA.

PAPER-HANGING MACHINE.

SPECIFICATION forming part of Letters Patent No. 718,015, dated January 6, 1903.

Application filed September 23, 1902. Serial No. 124,593. (No model.)

To all whom it may concern:

Be it known that I, DAVID M. MCCANLESS, a citizen of the United States, residing at Asheville, in the county of Buncombe, State of North Carolina, have invented certain new and useful Improvements in Paper-Hanging Machines, of which the following is a specification, reference being had therein to the accompanying drawings.

10 This invention relates to a paper-hanging machine, and particularly to a device for pasting, trimming, and applying to a surface a wall-paper.

The invention has for its object to provide 15 a construction of machine adapted to be carried in both hands of the operator and embodying therein means for pasting the paper, trimming the edges thereof, applying the paper to the surface to be covered, and finally 20 severing the paper at the proper point for each length as used.

The invention has for a further object to provide a novel construction of cutting device 25 for severing the paper, which device is normally held at one side of the paper by a latch and when released is automatically projected laterally of the paper to sever the same from the remaining pasted portion.

Other and further objects and advantages 30 of the invention will be hereinafter set forth, and the novel features thereof defined by the appended claims.

In the drawings, Figure 1 is a central vertical section through the machine; Fig. 2, a 35 plan thereof, and Fig. 3 a detail perspective of the cutting device.

Like letters of reference refer to like parts in the several figures of the drawings.

The letter A designates the frame of the 40 machine, which may be of any desired construction or configuration and preferably composed of the opposite side plates A', connected together by rods or tie-bolts, as usual, and provided at their lower portion with a handle A², carried by a cross-bar A³, secured at its opposite ends to the side plates A', while at one end of the machine a depending hanger A⁴ is provided for supporting the casing B for the roll of paper. This casing is formed with a 45 pivoted side wall B' for the introduction of the roll of paper, and when closed an opening B² is provided at the upper portion, so

that the roll may freely unwind within the casing to secure a continuous feed of paper. At the upper portion of the frame a bearing- 55 roller B³ is journaled in the side plates, over which the web of paper passes downward to and around the paste-drum C. This drum is removably supported in the side plates by means of the pivoted latch or hook C', engag- 60 ing the shaft or journal C² of the drum, and the latter is formed of any desired reticulated material C³, having a clothing thereon—for instance, cheese-cloth or similar material—which permits a free feeding of the paste to 65 the lower surface of the drum for application to the web of paper passing thereover.

Above the paste-drum a roller C⁵ is provided directly beneath a rotary cutter D, which bears against said roller to trim the edges of 70 the paper in its movement through the machine. These trimmers are supported upon a shaft D' for lateral adjustment thereon and adapted to be clamped in position by means of the screws D². The paper web passes over 75 the roll C⁵ and thence to the presser-roll E, having a rubber coating E' extending slightly above the upper edge of the frame, so as to press the pasted and trimmed paper into contact with the surface to which it is to be applied. This roll has its shaft E² pivoted in 80 the side plates A', similar to the other rolls.

Between the presser-roll and the trimmer a cut-off device F is provided for severing the paper at the end of each length, and this device is slidably mounted upon a cross-bar F', preferably of rectangular form and provided with a knife F², having a beveled edge F³ to produce a shearing cut in the lateral movement of the knife from right to left, and also 85 with a lug F⁴, adapted to engage the free end G of a latch which is pivoted to one of the side plates at G' and provided at its lower end with a handle G². The end of this latch is held in contact with the cutting device by 90 means of a tension-spring G³, while the device is held under tension by an elastic cord F⁵ or other equivalent device extending from a fixed point F⁶ upon one plate A' to a suitable attaching-point F⁷, provided upon the 100 sliding cutter.

In the operation of the invention it will be seen that the paper is pasted and trimmed in its passage through the machine, and when

applied to a surface by the presser-roller the draft on the paper continues to draw the same through the machine, thus automatically preparing the paper for application to the wall or ceiling immediately at the point and time of use. When the end of a length to be applied is reached, the latch may be tripped, permitting the cutting device to travel across the web of pasted paper, which is thereby severed between the trimmers and the presser-roller. It will be further seen that with a machine of this character much time and expense can be saved in the application of the paper and the waste thereof prevented, while the paste is applied to the paper immediately before its application to the surface to be covered, thus preventing the adhesion of the paste or pasted paper to the floor or furniture of the room. It will be also noted that the trimmers and cutting device are applied to operate after the paper has been pasted, as it can at that time be more readily cut and severed.

It will be obvious that changes may be made in the details of construction and configuration without departing from the spirit of the invention as defined by the appended claims.

Having described my invention and set forth its merits, what I claim, and desire to secure by Letters Patent, is—

1. In a paper-hanging machine, a paste-drum, a bearing-roller above said drum at one side thereof, a trimming-roll above the drum at the opposite side from the bearing-roller, a trimmer in contact with the trimming-roll, and a presser-roll at the opposite side of the trimmer from the paste-drum; substantially as specified.

2. In a paper-hanging machine, a pasting-drum, trimmers operating in contact with a trimming-roll, a presser-roll at the opposite side of said trimmer from the paste-drum, and a cutting device held under tension at one side of the machine and adapted to travel laterally across the same; substantially as specified.

3. In a paper-hanging machine, a pasting-drum, trimmers operating in contact with a trimming-roll, a presser-roll at the opposite side of said trimmer from the paste-drum, a cutting device held under tension at one side of the machine and adapted to travel later-

ally across the same, a pivoted latch adapted to engage and retain said cutting device at one side of the machine, and an elastic tension device for retracting said cutting device when released; substantially as specified. 55

4. In a paper-hanging machine, a frame, a casing supported at one end thereof to receive a roll of paper, a bearing-roller above said casing, a reticulated clothed paste-drum below said bearing-roller, an adjustable trimming knife and roller supported above said paste-drum at the opposite side from the bearing-roller, and an elastic covered presser-roller; substantially as specified. 60 65

5. In a paper-hanging machine, a frame, a casing supported at one end thereof to receive a roll of paper, a bearing-roller above said casing, a reticulated clothed paste-drum below said bearing-roller, an adjustable trimming knife and roller supported above said paste-drum, an elastic covered presser-roller, a cross-bar extending between the presser-roller and trimmer, a sliding cutter upon said cross-bar, an elastic device for drawing said cutter to one end of said bar, and a latch for retaining said cutting device under tension; 70 75 substantially as specified.

6. In a paper-hanging machine, a frame, a casing supported at one end thereof to receive a roll of paper, a bearing-roller above said casing, a reticulated clothed paste-drum below said bearing-roller, an adjustable trimming knife and roller supported above said paste-drum, an elastic covered presser-roller, a cross-bar extending between the presser-roller and trimmer, a sliding cutter upon said cross-bar, an elastic device for drawing said cutter to one end of said bar, a latch for retaining said cutting device under tension, a cross-bar upon which said trimming-knife is adjustably mounted, a clamp for securing said knife at its adjustment, a pivoted hook for removably securing said paste-drum in said frame, a cross-bar at the lower portion of the frame, and a handle provided upon said lower cross-bar; substantially as specified. 80 85 90 95

In testimony whereof I affix my signature in presence of two witnesses.

DAVID M. McCANLESS.
